UNITED STATES PATENT OFFICE.

WILLIAM WALLACE CORE, OF NEWARK, NEW JERSEY, ASSIGNOR TO THE PATENT APPLIANCE COMPANY, OF NEW YORK, N. Y., A CORPORATION OF NEW YORK.

DOOR-OPERATING DEVICE.

1,098,430.

Specification of Letters Patent.

Patented June 2, 1914.

Application filed January 5, 1912. Serial No. 669,662.

To all whom it may concern:

Be it known that I, WILLIAM WALLACE CORE, a citizen of the United States of America, and a resident of Newark, county 5 of Essex, and State of New Jersey, have invented certain new and useful Improvements in Door-Operating Devices, of which the following is a specification; reference being had to the accompanying drawings, 10 forming a part thereof.

This invention relates to an improvement in devices for operating doors, and particularly for operating such large heavy doors as are commonly employed in pier-sheds, 15 factories and the like.

The object of the invention is to provide a device of this character having means for varying the leverage of the pull on the door, so that as the door is swung from 20 a vertical toward a horizontal position the leverage increases in proportion.

I will describe my invention in the following specification and point out the novel features thereof in appended claims.

25 In the accompanying drawings: Figure 1 is a plan view of one embodiment of the invention. Fig. 2 is a front elevation of the same. Fig. 3 is an end elevation of the same. Fig. 4 is a front elevation of a modified form. Fig. 5 is a plan view and Fig. 6 is an end elevation of the arrangement shown in Fig. 4. Fig. 7 is a front elevation of another modified form of the invention having a horizontal drum shaft. 30 Fig. 8 is a plan view and Fig. 9 is an end elevation of the modification which is shown in Fig. 7. Fig. 10 is a front elevation of still another modified form having one counterweight. Fig. 11 is a front elevation and Fig. 12 is an end elevation of this 40 modification. Fig. 13 is a detail view of the differential winding drum and releasing mechanism for the counter weight of the upper door section.

45 Like characters of reference designate corresponding parts in all the figures.

In the embodiment of the invention illustrated in Figs. 1, 2 and 3, 1 represents a door such as is used on pier sheds, and is 50 composed of sections *a* and *b* slidably with respect to one another in a well known manner. The upper door section *a* is mounted on horizontal hinges 2, 2 which are secured to the wall of the shed. A chain or cable 55 4 is attached at its ends to the upper door

section near the lower edge of the latter, and at its middle portion the chain is attached to a movable pulley block 6, which carries a grooved pulley or sheave 8 arranged to rest on a hoisting cable 10. The cable is attached at both ends to a differential winding or hoisting drum composed of two sections 12 and 13 mounted on a vertical winding shaft 14. The drum sections 12 and 13 are mounted on the winding shaft 65 14 and connected to bevel gears 15 and 17, respectively, which mesh with bevel pinions 19 and 21 pivotally mounted on the interior of a worm wheel 26, thereby constituting a differential gearing. The hoisting cable 70 10 extends from the section 12 of this differential winding or hoisting drum over a fixed horizontal sheave 16 located above and behind the hinges 2, then passes forward over a vertical sheave 18 carried by a carriage 20, thence down under the sheave 8 in the block 6 then up over a vertical sheave 22 also mounted on the carriage 20, then around a fixed horizontal sheave 24 mounted above and in front of the extreme forward 75 position assumed by the lower edge of the door when swung up into horizontal position, then back to the section 13 of said hoisting drum.

The carriage 20 is provided with rollers 80 21^a which travel along the flange of an I-beam 23 extending forward from the end wall of the shed, and suspended from beams 25. This I-beam is shown in Figs. 2 and 3 but is omitted from Fig. 1 for the sake of 85 clearness.

The winding shaft 14 is operated by means of the worm wheel 26 on the differential gearing meshing with a worm 28 on a horizontal shaft 30, the latter being 90 provided with a chain wheel 32 over which passes the chain 34 which is in a convenient position to be grasped by the operator. When the chain is pulled to wind up the 95 hoisting cable, the cable is wound up at 100 each end according to the friction on each section of the winding drum, to pull the carriage forward and raise the door, said carriage automatically placing itself in a position vertically above the point of attachment of the hoisting cable to the door.

The two sections of the door are counterbalanced by counterweights 64 and 66, the counterweight 64 being of the proper size to counterbalance the lower section and the 110

counterweight 66 of the proper size to counterbalance the upper section. The weight 64 is connected to one end of a cable 68 which passes over a vertical sheave 70 and is connected at its other end to the winding drum 60. The counterweight 66 is connected to one end of a cable 72 which passes over a vertical sheave 74 and is connected at its other end to the winding drum 62. The winding drum 60 is so constructed that the counterweight 64 can be thrown out of action when only the top section of the door is to be swung out. This occurs when it is desired to close the lower half of the doorway and open the upper half to admit light and air.

The mechanism for throwing off the counterweight 44, that is the proper size to counterbalance the lower door section consists of a lever 50 pivotally mounted on the upper door section and connected to one end of a cable 44 passing over sheaves 48 and 46 and pivotally connected to one end of a latch lever 36. This latch lever is held in the path of a hooked lug 40 on the periphery of the counterweight drum 60 by a weight 52 to which it is connected by a cable 54 passing over a sheave 56. The arrangement of the lug 40 with the latch lever 36 prevents the rotation of the drum 60 and renders the counterweight 64 inactive until the latch lever is moved out of the path of the lug and the drum released. The locking of the drum 60 does not interfere with the raising and lowering of the upper door section, and the free rotation of the winding shaft 14 and the drum 62 because the drum 60 is arranged to be automatically uncoupled from the shaft 14. The drum 60 is rotatable on the winding shaft 14 and its hub is internally threaded to receive the correspondingly threaded hub 23^a of an arm 25 which is adapted to engage a lug 27 on the upper face of the winding drum 60. The hub of this arm is slidable on a key 29 on the winding shaft, and when the lug 40 is in engagement with the end of the lever 36 the drum 60 is held against rotation. Therefore when the winding sheet is rotated the arm 25 moves away from the lug 27. The pitch of the thread on the hub is such that when the arm 25 has made one revolution it will have moved axially of the shaft a distance sufficient to allow it to clear the end face of the lug 27. Further rotation of the shaft 14 in this direction moves the arm farther away. If only the upper door section is raised the counterweight for the lower door section is suspended by the drum 60 due to the fact that the lug 40 is in engagement with the end of the lever 36, said drum rotating freely on the winding shaft 14 as above indicated. Rotation of the shaft 14 in the opposite direction brings the arm 25 back into engagement with the lug 27 to connect the

counterweight to the winding shaft when the door sections are returned to their original lowered positions.

When it is desired to raise both door sections, the lower section is pushed up to engage the lever 50, which, through the cord 44 pulls the end of the lever 36 out of the path of the lug 40 on the drum 60. This allows the drum 60 to revolve with the shaft 14 in the same manner as the drum 62, drum 60 controlling the counterweight 64, which is for the lower door section, and drum 62 controlling the counterweight 66, which is for the upper door section; thus both counterweights are in action.

When it is desired to raise only the upper door section leaving the lower door section in place, the lever 50, not being interfered with remains in a position which allows the lever 36 to stay in engagement with the lug 40 of the drum 60. Now, if we attempt to operate the mechanism, the shaft 14 with the drum 62 will revolve, allowing the upper section to be counterbalanced by the counterweight 66 through its connection with the cable 72, while the lug 40 of the drum 60 remains in engagement with the lever 36 and thereby suspends the counterweight 64 of the lower door section, thereby nullifying its counterbalancing effect, which is not needed because the lower section is not raised, the drum 60 being freed from driving relation with the arm 25, as described above.

The winding drums for the counterweights 64, 66 are proportioned to the winding drums for the hoisting cable according to the amount of travel and head room in any particular instance.

When the door is closed it hangs in a vertical position, and the carriage 20 is in its rearward position near the wall of the shed. In this form of the device, when the hand chain 34 is pulled to rotate the worm shaft, the cable 10 is wound up. Only a slight amount of horizontal force is necessary to start the door to swing upwardly, but the nearer it approaches the horizontal position the greater its leverage on the hinges and the greater the force necessary to raise it. As the door swings open the carriage 20 automatically rolls away outwardly from the hinges so that the cable 10 always exerts its pull vertically and at a constantly increasing leverage on the door as it rises. By having the winding drums 60 and 62 of greater diameter than that of the winding drums 12 and 13, in the present instance about two to one, the counterweights 64 and 66 travel downward 2 inches to every inch of rise of the pulley-block 6, it being understood that the drums 12 and 13 wind up both ends of the cable 10 at once according to the requirements.

In the modification shown in Figs. 4, 5 and 6, the door 1 is composed of sections *a* and *b*

5 hinged at 2 and connected by a cable 4 to a block 70 similar to the manner shown in Fig. 2. An endless cable 72 supports a movable pulley 74 mounted in a block 70 and passes over vertical sheaves 76 and 78 in a carriage 80, then around a horizontal idler 82 and a movable pulley 84, the latter being free to move with the cable and provided with a hook 86 to which one end of a cable 10 88 is attached. The cable 88 passes over a horizontal fixed idler 89, and its other end is connected to a winding drum 90 on a vertical winding shaft 92. The winding drum is operated by a worm wheel 94 on the winding shaft, said worm wheel meshing with a worm 96 on a shaft 97. On another part of this shaft is a chain wheel 98, operated by a chain 100.

15 Mounted on the shaft 92 are a pair of winding or counterweight drums 102 and 103 of larger diameter than that of the winding or hoisting drum 90. The drum 102 is connected to one end of a cable 104, which passes over a vertical idler 105 and is connected at its other end to a counterweight 106. The drum 103 is connected to one end of a cable 107, which passes over a vertical idler 108 and is connected at its other end to a counterweight 109. The relative diameters of the winding drums is such as will produce the desired movement of the counterweights with respect of the movement of the door in any particular instance. With this modification a counterweight releasing mechanism is also provided modified in accordance with the difference in the hoisting mechanism, but not shown in the drawings.

20 In the modification shown in Figs. 7, 8 and 9, the door is attached by a cable 110 to a block 112. A cable 113 is attached to the block 112 and passes over a vertical idler 114 in a traveling carriage 124, thence around a fixed horizontal idler 115 to a winding or hoisting drum 116 on a horizontal winding shaft 117. The winding shaft 117 is provided with a worm wheel 118 which meshes with a worm 119 on a shaft 120, said shaft being provided with a chain wheel 121 over which a chain 122 passes in a position to be grasped by the operator. The carriage 124 is connected to one end of a cable 126, which is connected to a conical spiral winding drum 128 on the winding shaft 117. The conical spiral drum is so shaped that the radius at which the rope pulls at any moment is such as to move the carriage horizontally with a speed proportional to the sine of the angle which the door makes with the vertical. A pair of counterweights 130 and 132 are provided connected respectively to one end of the cables 134 and 136. The cable 134 passes over a vertical idler 138 thence over a horizontal idler 140, and is connected at its other

end to a winding drum 142 on the winding shaft 117. The cable 136 passes over a vertical idler 144, thence over a horizontal idler 146 to a winding drum 148 on the shaft 117. In this construction the counterweights 70 are connected to small winding drums, whereas the hoisting cable is connected to a winding drum of greater diameter than that of the counterweight drums, and the forward movement of the carriage is controlled by the action of the drum 128.

10 The drum 128 may be provided with a section having a rapidly reducing radius adjacent to the largest section of the drum to allow the hoisting cable to pass onto a small diameter as quickly as possible so as to give the slack for unhooking the cable 110 without moving the carriage 124 toward the wall too rapidly while so doing.

15 The counterweight 132 is thrown out of action in this modification similarly to the manner described above, but the mechanism is necessarily somewhat different to suit the present location of the various parts, this portion of the mechanism being not shown 90 in the drawings.

20 In the modification shown in Figs. 10, 11 and 12, the door is attached by a cable 150 to a pulley 152 supported by a cable 154. The cable 154 is connected at one end to a carriage 158 and passes under the pulley 152, then over the vertical idler 157 in the traveling carriage 158, the fixed horizontal driving sheave 161, the movable pulley 162, the fixed idlers 163 and 160 back to the carriage 158. The movable pulley 162 is connected to one end of a cable 164, which passes over a vertical idler 166 and is connected at its other end to a counterweight 168. The driving sheave 161 which may be a grip sheave 105 of well known form is mounted on a shaft 170, which is provided with a bevel gear 172 meshing with a bevel gear 173 on a shaft 174. If desired a worm and worm wheel may be substituted for the bevel gears. The shaft 110 174 is provided with a chain wheel 176 operated by a chain 178. In this form of the device there is only one counterweight, which is connected to the movable pulley 162 on the hoisting cable.

25 115 What I claim is:

1. The combination with a horizontally pivoted door, of a traveling carriage having a horizontal path of movement, a shaft, a differential on said shaft, a pair of drums 120 connected to said differential, a cable having its ends secured to said drums, said cable being looped down through said carriage and secured to the door, the arrangement being such that the operation of the differential 125 automatically adjusts the position of the carriage as the door is raised and lowered.

2. The combination with a horizontally pivoted door, a counterweight therefor, and 130

a counterweight cable connecting the two, of a support above the door extending outwardly from the plane of the door opening, a carriage movably mounted on the support, means for driving the carriage to adjust its position on the support and means dependent upon the raising and lowering of the door for actuating the driving means, said carriage being operatively connected to the door by said counterweight cable.

3. The combination with a horizontally pivoted door with a support above the door extending at right angles to the plane of the door opening, a counterweight for the door, a carriage movably mounted on the support, means guided by the carriage connecting the door and the counterweight, means for driving the carriage to adjust its position on the support, and means dependent upon the raising and lowering of the door for actuating the driving means.

4. The combination with a horizontally pivoted door, of a traveling carriage having a horizontal path of movement at substantially right angles to the plane of the door opening, a counterweight for the door, a cable connected to the door near its lower edge, passing over the said carriage and connected to the counterweight at its opposite end, a relatively stationary horizontal shaft, means operatively connected thereto for raising and lowering the door, said carriage being operatively connected to said shaft whereby the position of the carriage is positively determined by the position of the door.

5. The combination with a horizontally pivoted door, of a traveling carriage having a horizontal path of movement at substantially right angles to the plane of the door opening, a counterweight for the door, a cable connecting the lower edge of the door to the counterweight and passing over said carriage, a relatively stationary horizontal shaft, means for operating the shaft to raise and lower the door, differential gears on the shaft and means dependent upon the differential gears for adjusting the position of the carriage whereby the carriage is maintained substantially over the point of connection between the cable and the door.

6. The combination with a horizontally pivoted door, a rail above the door extending outwardly from the plane of the door opening, a carriage movable on the rail, guide pulleys mounted on the carriage, fixed pulleys beyond the limits of the carriage movement and near its respective ends, a pulley affixed to the door, a vertical shaft rotatably supported above the door opening at the inner end of the rail between the fixed pulleys, a winding drum secured to the shaft, a counterweight for the door, a cord attached to the counterweight and secured to and adapted to be wound on the drum, a

pair of differentially connected drum sections mounted on the shaft and a cord secured at its ends to and wound on the respective drum sections and extending from one of said sections over one of said fixed pulleys thence over a guide pulley of the carriage, around the door pulley, over a second guide pulley of the carriage and over the other fixed pulley to the other drum section.

7. The combination with a horizontally pivoted door, a rail above the door extending outwardly from the plane of the door opening, a carriage movable on the rail, guide pulleys mounted on the carriage, fixed pulleys beyond the limits of the carriage movement and near its respective ends, a pulley affixed to the door, a vertical shaft rotatably supported above the door opening at the inner end of the rail between the fixed pulleys, a winding drum secured to the shaft, a counterweight for the door, a cord attached to the counterweight and secured to and adapted to be wound on the drum, a pair of differentially connected drum sections mounted on the shaft and a cord secured at its ends to and wound on the respective drum sections and extending from one of said drum sections over one of said fixed pulleys thence over a guide pulley of the carriage around the door pulley, over a second guide pulley of the carriage and over the other fixed pulley to the other drum section, whereby the carriage is driven by the cord to occupy a position substantially above the door pulley as the door is raised and lowered.

8. The combination with a horizontally pivoted door, a support above the door extending outwardly from the plane of the door opening, a carriage movable on the support, fixed cable guides near the respective ends of the support, other cable guides on the carriage and on the door, a winding drum rotatively mounted between the fixed cable guides, a counterweight for the door, a cable attached to the counterweight and arranged to be wound on the drum, differentially connected drum sections operatively connected to the first-named drum and a cable secured at its ends to and wound on the respective drum sections and extending from one of said drum sections over one fixed cable guide, thence over a cable guide of the carriage, a cable guide on the door, a second cable guide on the carriage and the other fixed guide to the other drum section.

9. The combination with a horizontally pivoted door, a support above the door extending outwardly from the plane of the door opening, a carriage movable on the support, fixed cable guides near the respective ends of the support, other cable guides on the carriage and on the door, a winding drum rotatively mounted between the fixed

cable guides, a counterweight for the door, a cable attached to the counterweight and arranged to be wound on the drum, a cable coöperating with the several guides and means associated with said drum to which the ends of the cable are secured for automatically varying the position of the carriage, as the door is raised and lowered.

10. The combination with a horizontally pivoted door, a support above the door extending outwardly from the plane of the door opening, a carriage movable on the support, fixed cable guides near the respective ends of the support, other cable guides 15 on the carriage and on the door, a winding drum rotatively mounted between the fixed

cable guides, a counterweight for the door, a cable attached to the counterweight and arranged to be wound on the drum, a cable coöperating with the several guides and means operatively connected to the winding drum comprising sections to which the respective ends of the cable are secured for automatically adjusting the position of the carriage as the door is raised and lowered.

15. In testimony whereof I have signed my name to this specification in the presence of two subscribing witnesses.

W. WALLACE CORE.
